MAX C. MILLER, OF CUMBERLAND, RHODE ISLAND

KNITTING MACHINE

Application filed September 15, 1926. Serial No. 135,570.

The invention relates to knitting machines and more particularly concerns the relationship of the needles with the devices for knocking over the loops and for holding down the fabric as the needles rise.

The object of the invention is to provide a new and improved needle and web holder combination which will be simple in construction and efficient in operation.

10 A further object of the invention is to associate needles and web holders in a knitting machine in such a manner as to make possible the more efficient production of line gage appearing fabric, this effect being secured 15 specifically by making the sinker wales relatively small as compared to the needle wales.

Another object of the invention is to secure a more rapid relative movement of the web holder and needle to draw loops previously 20 formed beyond the back line of the needles as the needles are advanced to take new yarn.

With these objects in view, one feature of the invention consists in the provision of means for introducing a yield into the relative 25 movements of the needles and web holder hooks as these parts are moved relatively to force the previously formed loops beyond the back line of the needles during the advance of the needles to receive new yarn. By 30 this means it is made possible to knit with very tender yarns and the delicate adjustments heretofore necessary in the relative movements of the needle and web holder in accordance with the length of loop drawn 35 down by the needle can in large measure be done away with.

More specifically a sideways movement is imparted to the forward portion of the needle shank away from the web holder hook to 40 draw the loop held on the knock-over into the web holder notch so that the loop is held down by the hook and beyond the back line of the needles as the needle advances to take new yarn. The spring inherent in the needle 45 shank is sufficient to allow considerable yield between the needle and web holder hook making unnecessary any very close adjustment in accordance with the length of loop even while knitting with very tender yarns.

50 Furthermore, since the needle is swung or

flexed outwardly from a point well down on the shank a very rapid movement of the needle at the knock-over level to draw out the loops may be obtained with the use of a relatively slight angle cam, thus conducing to 5 more efficient and rapid operation while reducing wear and tear on the parts.

Another feature of the invention consists in the provision of a stationary web holder adapted to cooperate with a needle having 60 the mode of operation above described.

The various features of the invention together with the advantages obtained thereby will be readily understood by one skilled in the art from the following description taken 65 in connection with the accompanying drawing which illustrates one embodiment of the invention as applied to a circular latch needle knitting machine. The Fig. 1 is a sectional view of a portion of a needle cylinder 70 with its cooperating knitting elements, so much only of the machine being illustrated as is necessary to show the connection of the present invention therewith.

The circular knitting machine illustrated 75 in the drawing comprises a rotatable needle cylinder and a circular series of latch needles slidably mounted in grooves in the periphery of the cylinder. A series of stationary web holders are provided to cooperate with the 80 needles, said web holders being fixedly mounted in grooves formed in the top of the needle cylinder. Means are provided for flexing the needles outwardly away from the web holders as the needles rise to take new 85 yarn so that the needle loops are drawn out into the web holder hooks and reformed against the spring pressure of the needle shanks. The web holder hooks are thus made effective to draw out the previously formed 90 loops beyond the back line of the needles.

Referring specifically to the drawing, an ordinary type of latch needle is indicated at 1, a series of stationary web holders at 2 and the rotatable needle cylinder on which these 95 elements are carried is indicated at 3. The needles are held in their slots in the needle cylinder 3 by means of the usual spring bands 4. A series of pins 5 are slidably mounted in holes in the needle cylinder 3 to make contact 100

at their outer ends with the shanks of the needles and are adapted to be acted upon at their inner ends to flex the needles outwardly by a cam 6 carried on a cylinder 7 within the needle cylinder 3.

- 5 The stationary web holders 2 are provided with ordinary knock-over surfaces 8 and web holder hooks 9. The hooks are so constructed and placed as not to interfere with the feeding 10 of the new yarn to the needles which are retracted in the usual manner to knock over the new loops on the web holder nibs.

As each needle is raised again to the clear position preparatory to taking new yarn it 15 is flexed outwardly causing the loop held on the needle to be drawn outwardly into the web holder notch and be reformed to the fullest extent of the yarn contained therein against the spring pressure of the needle 20 shank. At the same time by drawing the sinker wale loops tightly into the webholder hooks the hooks are rendered effective to hold these loops from rising with the needle and the previously formed loops held by the contact 25 of the webholder hooks with the fabric are carried beyond the back line of the needles.

The cam 6 is brought into active operation to flex the needles outwardly only during the 30 upward movement of the needles in a knitting wave to receive new yarn. When the needles are raised more than the usual amount to inactive position the recess 1^a in the needle is brought into alignment with the pin 5 so that 35 these needles are not affected by the cam 6.

Inasmuch as the pins 5 come in contact with the needle shanks at a point some distant below the knock-over level a yield is introduced into the relative movement of 40 needle and web holder by virtue of the spring qualities of the needle shank. Furthermore, since a small movement of the pins 5 will cause a relatively large movement of the upper end of the needle it is possible with a relatively light angle cam 6 to secure a very rapid 45 relative movement of the web holder and needle to draw loops previously formed beyond the back line of the needles as the needles are advanced to take new yarn.

50 The machine is adjusted to produce the length of loop desired before starting the machine by raising or lowering the needle cylinder in the usual manner to cause the needles to draw their loops the required distance below the knock-over level. A corresponding 55 adjustment of the cam 6 to flex the needles in proportion to the length of loop drawn is secured by the shift of the point of contact of the pins 5 with the periphery of the cam 6 mounted on the stationary cylinder 7 as the needle cylinder is raised or lowered. Provision is made for a further adjustment of the 60 flexing movement of the needles if necessary by raising or lowering the cylinder 7. However, the yield thus provided due to the spring

qualities of the needle shank is sufficient to permit the use of tender yarns without making the very close adjustments necessary in present day commercial machines.

The mode of operation of the needles and web holders in combination as above described embodied in a circular knitting machine is as follows:

The needles are advanced and retracted by their cams in the usual way. In the drawings 75 the low or knock-over position of the needle is illustrated in full lines. The highest position of the needle illustrated in dotted lines at 10 is that in which idle needles are placed when thrown out. The intermediate position 80 illustrated in dotted lines at 11 is that to which the needles are ordinarily raised to clear the latches of the previously knit row of loops and to receive new yarn. A series of dotted positions for the needle clearly 85 illustrates the effect of the cam 6 in flexing the needles outwardly as they start to rise so that the loops are drawn into the web holder notches during the upward stroke of the 90 needles and reformed against the spring pressure of the needle shanks to the fullest extent of the yarn contained therein. For this purpose, the cam 6 is moved in time relation to the needle actuating cams forming the knitting 95 wave. When the needles reach their normal high position they are permitted to swing inwardly again to the position shown at 11 so that the new yarn may be fed to the needles at the intermediate or yarn taking level without interference by the web holder hooks. 100 The needles may then be retracted to the low position drawing new loops through the old loops which act as the needles descend to close the latches and then slide off the ends of the needles.

105 It will be seen that when needles are raised to the inactive position 10 the slot 1^a in the needle shank will coincide with the pin 5 so that the cam 6 will be rendered inoperative to flex these needles.

110 Although the invention has been described and illustrated as embodied in a circular knitting machine, obviously it may be used to advantage in other types of knitting machines and especially in flat bed machines of the Lamb type.

115 The nature and scope of the invention having been indicated and one embodiment thereof described, what is claimed is:

1. In a knitting machine, the combination 120 of a series of needles, a series of stationary web holders, means for flexing the needles away from the web holders during the upward thrust of the needles to reform the needle wale loops against the spring pressure of the needle shanks, and means for rendering the flexing means inoperative when the needle is in its inactive position.
2. In a knitting machine, the combination 125 of a series of needles, a needle bed in which

- the needles are carried, a corresponding series of stationary web holders, a series of pins adapted to engage the needle shanks, and a cam adjustable in accordance with the size 5 loop to be drawn for actuating the pins to flex the needles away from the web holders to reform the loops against the spring pressure of the shanks.
3. In a circular knitting machine, the combination of a needle cylinder, a series of 10 needles slidably mounted thereon, a corresponding series of stationary web holders mounted on the cylinder, hooks formed thereon, a series of pins mounted in the cylinder and adapted to engage the needle shanks, a tube 15 mounted within the needle cylinder, a cam mounted on the tube adjustable in accordance with the size of loop to be drawn for actuating the pins to flex the needles away 20 from the web holders to reform the loops under a yielding spring pressure against the webholder hooks. 85
4. In a circular knitting machine, the combination of a needle cylinder, a series of 25 needles slidably mounted on the outer periphery thereof, a corresponding series of stationary web holders mounted on the cylinders, hooks formed thereon, a series of pins slidably mounted in the cylinder and adapted 30 to engage the needle shanks, a tube mounted within the needle cylinder, a cam mounted on the tube adjustable in accordance with the size of loop to be drawn for actuating the pins to flex the needles outwardly from the 35 web holders to reform the loops under a yielding spring pressure against the webholder hooks. 90 95
5. In a knitting machine the combination of a series of needles, a needle bed in which 40 the needles are carried, a corresponding series of stationary webholders for knocking over loops held on the hooks of the retracted needles, hooks formed on the web holders, and means adapted to engage and flex the 45 needle shanks outwardly during the advancing movement of the needles to reform the loops on the webholder hooks against the spring pressure of the needle shanks. 100 105
6. In a knitting machine the combination 50 of a series of needles, a needle bed in which the needles are carried, a corresponding series of stationary webholders for knocking over the loops held on the hooks of the retracted needles, hooks formed on the webholders, a 55 series of pins adapted to engage and flex the needle shanks outwardly to reform the loops by the spring pressure of the needle shanks against the webholder hooks, and a cam for actuating the pins. 110 115
- 60 65 7. In a knitting machine the combination of a series of needles, a needle bed in which the needles are carried, a series of stationary webholders for knocking over loops held on the hooks of the retracted needles, hooks formed on the webholders, and means ren- 120
- dered active upon raising the needles to flex the needles outwardly to hold the loops yieldingly extended against the webholder hooks. 70
8. In a circular knitting machine the combination of a needle cylinder, a series of 75 needles slidably mounted thereon, a corresponding series of stationary webholders for knocking over loops held on the hooks of the retracting needles, hooks formed on the webholders, and means rendered active upon raising the needles to flex the needles outwardly to reform the loops under the yielding spring pressure of the needle shanks against the webholder hooks. 80
- In testimony whereof I have signed my name to this specification. 85
